UNITED STATES PATENT OFFICE

2,213,258

COMPRESSOR

Ralph E. Lamberton, Michigan City, Ind., assignor to Sullivan Machinery Company, a corporation of Massachusetts

Application April 30, 1937, Serial No. 140,031

13 Claims. (Cl. 230—231)

My invention relates to pumps or compressors, and more particularly to compressors for air or other gaseous fluids.

In the design of air compressors it is important to provide for efficient cooling, smooth air flow, adequate air passageways, freedom from leakage, security against distortion as the parts heat up in operation, accessibility to the valves without disconnecting piping, convenient but effective valve assemblies, and other features of sound design, and in the attainment of certain of these desiderata, loss of others is frequently encountered in actual practice.

It is an object of my invention to provide an improved pump or compressor. It is another object of my invention to provide an improved cylinder and head construction for a pump or compressor. It is a further object of my invention to provide an improved valve mechanism for a pump or compressor. More specifically, it is an object of my invention to provide an improved pump or compressor design in which the portion of a pump cylinder or cylinders adjacent which the piston travels shall be free from bosses which may tend to cause distortion and oil pumping, in which inlet and discharge connections shall not have to be disturbed to remove the valves, in which the cylinder or cylinders shall extend up far enough above the upper limit of piston travel to provide an adequate recess for valve seats and cages, sufficient area for air passages, and appropriate connections for the air inlet and discharge connections. Again, it is an object of my invention to provide an improved pump or compressor design in which the flow passages may be made of large area and be streamlined to promote smooth and unimpeded flow. Further, it is an object of the invention to provide an improved design particularly, but of course not solely, adapted to compression stages above the first, in which sealing at the necessary points may be effected readily but surely and yet without complication of design. And another object of the invention is so to relate the unloading mechanism to the other parts of the cylinder and valve mechanism that air flow will be unimpeded thereby during normal loaded operation. Other objects and advantages of the invention will hereinafter more fully appear.

In the accompanying drawings, in which one embodiment which my invention may assume in practice has been shown for purposes of illustration,

Fig. 1 is a central vertical section through the top of a compressor cylinder, cylinder head, and

valve mechanism, the plane of the section bisecting the inlet and discharge connections;

Fig. 2 is a horizontal section, looking downwardly, on the plane of the section line 2—2 of Fig. 1;

Fig. 3 is a horizontal section, looking upwardly, on the planes of the section line 3—3 of Fig. 1, showing the lower face of the valve cage element which provides the inlet valve seat and the discharge valve guard; and further showing 10 a portion of the discharge passage;

Fig. 4 is a horizontal section, looking downwardly, on the plane of the section line 4—4 of Fig. 1, showing a section through the cylinder at a point below the location of the valve devices 15 therein and illustrating details of the discharge passages;

Fig. 5 is a view from above, of the lower plate of the valve mechanism;

Fig. 6 is a side elevation of the top part of the 20 pump cylinder and head, viewed from the intake side;

Fig. 7 is a radial section on an enlarged scale through the inlet and discharge valves, showing details of construction;

Fig. 8 is an elevation of the head element proper, with the same removed from the cylinder, and

Fig. 9 is a detail fragmentary section on a plane corresponding to the line 9—9 of Fig. 3, 30 showing the mode of valve guiding.

Referring to the drawings, and first to Fig. 1 of the latter, it will be noted that a cylinder member 1, of which only the upper portion is shown, provides a bore 2 in which a piston 3 is reciprocable; and, above the upper limit of piston travel, is provided with an enlarged bore 4 coaxial with the cylinder bore 2 and opening through the top of the cylinder member. Within the enlarged bore 4 is housed a composite inlet and discharge 40 valve mechanism generally designated 5 and later more fully described, this resting upon a gasket 6 which is supported by the plane annular shoulder 7 extending inwardly from the lower end of the wall of the enlarged bore 4 to 45 the upper end of the counter-bore 8 which lies at the extreme upper end of the cylinder bore 2. A cylinder head element 9 extends for most of its length into the enlarged bore 4 and has a radial peripheral flange 10 which overlies the 50 top of the cylinder member 1 outside the enlarged bore 4. There is a sealing gasket 11 between this flange and the outer end of the cylinder member 1.

The shoulder 7 is provided with an annular 55

groove 13 substantially midway between its sides which communicates with a series of arcuate passages 14 which extend downwardly and then outwardly as well shown in Fig. 7, and communicate at their outer, lower ends with a passage 15 which lies outside the enlarged bore 4 and increases in width (radial dimension) and in height (dimension parallel to the cylinder axis) from a point opposite the discharge connection 16 to the communication of its opposite branches 15^a and 15^b with said connection. Webs 17, of which some are sloped in a direction to facilitate the flow through the passages 14 towards the discharge connection 16, separate the passages 14 from each other. It will be noted that the discharge connection 16 is arranged in the portion of the cylinder member 1 which lies at the outer end of the latter, and that the valve mechanism 5 and head proper 9 can be removed from the cylinder without affecting the discharge connection or any piping connected to the latter by means engaging in the threaded holes of which one is shown at 18. It will be observed, moreover, that with uniform fluid discharge through the passages 14 there will be a smooth and unrestricted delivery of fluid to the discharge 16 due to the vaning effect of the webs 17 and the radial and axial increase in dimension of the discharge passages 15^a and 15^b. A web 19 may be provided adjacent the discharge opening to direct the oppositely moving streams of fluid from the passages 15^a and 15^b without substantial counterflow into the discharge opening.

35 An intake connection 21, herein shown as equipped with an air cleaner, is arranged on the cylinder member 1, herein diametrically opposite the discharge opening 16, and is provided with branches 21^a and 21^b extending oppositely arcuately for a substantial distance around and in communication with the enlarged bore 4. A streamlined web 22 splits the inflowing fluid.

Deferring for a short time longer the description of the valve mechanism 5 which lies between the head member 9 and the cylinder bore 2, it may be noted that the cylinder head 9 is divided by a curved wall 24 into a generally crescent-shaped chamber 25 having an open top and a closed bottom and acting both to increase the radiation and as a means of reducing heat transfer to incoming air, and a fluid inlet passage 26 having an upper wall 27 and a ported lower wall 28, each of said walls recessed to provide a central pocket, as at 29 and 30 respectively, to reduce the metal in the head and to improve the heat-insulating characteristics of the head. The head 9 is open laterally opposite the passage portions 21^a and 21^b, to provide for inlet into the fluid inlet passage 26, and the bottom of the head is provided with a series of openings 31 in a generally annular arrangement to the outside of and surrounding the pocket 30, these openings connecting the inlet passage 26 with inlet ports in the valve mechanism 5, as will now be shortly described. A rib 32 is formed in the head opposite the rib 22 and is streamlined with the latter, and a pair of streamlined spacing ribs 33 and a dividing rib 34 connect the upper and lower walls of the inlet passage. The bottom wall of the head 9 is elevated at its central portion 28^a above the pocket 30 and within the zone surrounded by the annularly arranged series of ports 31. The ribs 22 and 32 split the entering air stream, and the divided streams are again divided by the ribs 33, so that portions of each

stream enter the port 31 nearest the inlet connection, and larger portions, including portions which pass between ribs 33 and over the wall portion 28^a, enter the ports 31 which lie outside the ribs 33 and which are separated by the dividing rib 34. It may be noted that the wall and rib conformation provides for a smooth flow to the passages or ports 31, with flow areas proportioned at different points to the volume of fluid to be accommodated.

10 The valve mechanism 5 may now be described. This comprises a relatively thick, circular upper plate or block 35 and a relatively thin lower plate 36. The upper plate 35 provides a seat for an inlet valve and a guard for a discharge valve. The lower plate 36 provides a guard for an inlet valve and a seat for a discharge valve. The inlet valve mechanism is arranged to the inside, radially speaking, of the discharge valve, and herein single annular-type valves are shown for purposes of illustration. The plate 35 is traversed by an annularly arranged series of ports 37, separated from each other by bridges or ribs 38, of which there are three shown in this embodiment. The ports 37 heretofore described communicate with the upper ends of the ports 31. At their lower ends the ports 37 open through an annular valve seat area 39, comprising portions 39^a and 39^b respectively at opposite sides of the ports 37. An annular inlet valve 40 is adapted to seat upon the seat areas mentioned and is herein pressed towards its seat by an annular flexed spring 41, herein of the multiple-unit, laminated type, received in a groove 42 in the upper face of the plate 35. Plate 36 is traversed by radially-spaced series of annularly-arranged, arcuate inlet passages 43 and 44 respectively opening at their inner and outer edges into the groove 42. Ribs 45 and 46 divide the several passages 43 and 44 from each other and either or both sets of ribs may constitute guides for the inlet valve 40 and the valve spring or springs 41. Herein the ribs 45 are the only ones which so function, ribs 46 being cut back and the valve and spring being guided at their outer peripheries only.

35 The plate 35, to the outside of the ports 43, is provided with a generally annular groove 48 opening through its lower surface and herein subdivided partially by six radially extending ribs 49 which support an annular valve guard and passage forming member or portion 50 in spaced relation from the sides and bottom (top, as arranged) of the groove 48. As shown best in Fig. 9, the ribs 49 are cut away as at 51 and member 50 is recessed as at 52 to provide a complete annular groove to receive a discharge valve 53, an annular spring 54 and a spring-abutment plate 55. The plate 55 engages an annular surface 56 on the ribs and member 50, and right-angledly arranged surfaces 57 on the ribs center the plate 55 and the spring 54 and valve 53. The plate 36 is traversed by an annular series of ports 60 communicating at their lower ends with the cylinder bore 2 at the outer periphery of the latter and opening at their upper ends through a valve seat surface 61 with which the valve 53 cooperates. Outside of the ports 60 the plate 36 is traversed by still another annular series of arcuate ports 62, opening at their lower ends into the annular groove 13 and communicating at their upper ends with the outer portions of the annular groove 48. It will be evident that the construction described permits discharge of fluid passing to the inside of the discharge valve 75

53 through the spaces to the rear, above and to the outside of the member or portion 50, herein constituting passages generally designated 63, and fluid may also pass directly through the 5 spaces 64 radially outwardly to the ports 62. Fluid may also obviously enter the cylinder 2 past both edges of the inlet valve 40.

The plates 35 and 36 are fixed to each other by screws 65 mounted in shouldered bores 66 in plate 35 and entering threaded holes in plate 36. Dowels 67 mounted in holes 68 and 69 respectively formed in the top of plate 35 and in the bottom of head 9 maintain the desired relation between the valve mechanism and the head. As above noted, the gasket 11 seals the head and the top of the cylinder member and so prevents leakage if the cylinder be a high pressure one. The ground plane surfaces of the plates 35 and 36, pressed together by the screws 65, preclude leakage between the inlet and discharge. As noted also, the discharge valve seat member 36 rests upon a gasket 6, and set screws 70 mounted in the head 9 press upon the top of member 35 and so hold the discharge valve seat tight on the gasket. This prevents cylinder discharge pressure from leaking back into the cylinder and into the inlet passage. The set screws 70 are capped with solid nuts 71 and provided with gaskets 72 to prevent inlet pressure, if this be above atmospheric, as in a high pressure cylinder, leaking to atmosphere.

Unloading means cooperating with the inlet valves is provided. This is generally designated 75 and includes an actuating piston 76 movable in a cylinder 77 mounted on the top of the head 9 by means of a mounting plate 78, held to the head by screws 79 and to which the cylinder 77 is held by screws 80. Double packings 81 and 82 prevent respectively leakage from the cylinder 77 to the inlet space of the pump and leakage of pressure from the inlet space of the cylinder 1, when the latter is used as a high pressure cylinder, to the cylinder 77. Head 9 has a chamber 84 in the top thereof beneath the plate 78, which has a gasket 85 between it and the head 9 to prevent leakage, and chamber 84 receives the actuating plate 87 for three fingers 88 which pass through openings 89 in the ribs 33 and 34 and openings 90 in the plate 35, in the ribs 38 of the latter, into a position to engage and force open the inlet valve. A connection 91, controllable by any suitable pilot mechanism (not shown) conducts operating fluid to and from the cylinder 77, and a spring 92, herein shown as a transversely flexed wafer or ribbon spring acts between the bottom of the plate 87 and the top of the head 9, within the recess 84 in the latter. The operating fingers 88 are entirely shrouded by the streamlined ribs or bosses in the head and by the ribs in plate 35 except at their tip ends, at which points it may be noted they extend in the same direction as the fluid stream passing between the passage 26 and the cylinder 2.

It will be obvious how the device described operates. Upon the downward or suction strokes of the piston 3 air or other fluid being pumped will flow from passage 21 to passages 21^a and 21^b, through passages 31, past the inlet valve 40 and through the passages or ports 43 and 44 into the cylinder. Upon the compression strokes of the piston the fluid will be discharged through the ports 60, past the valve 53, through the passages 63 and 64, ports 62, groove 13, passages 14, passages 15^a and 15^b and to the discharge 16. When operating fluid is supplied to cylinder 77, piston

16 will cause fingers 88 to open, and maintain open the inlet valve 40, and the air or other fluid will flow back and forth between the cylinder bore and the inlet space.

It will be evident that a very effective pump is provided by the apparatus described. While the valve cage elements 35 and 36 are separate pieces, they are held in the proper relation to each other and to the head as above described and the composite structure provides smooth, uninterrupted streamline air passages both for entering and for discharging air. All screws are enclosed in or covered by streamline bosses, and the unloading fingers project only slightly into the air passages and then only in the direction of flow. The various ribs are directed in the manner best calculated to guide flow in the most desirable direction. The passages are proportioned to accommodate the flow requirements adequately and smoothly. The keeping of the discharge passages entirely out of the head and the provision of the spaces in the head, and especially the space 25, prevent to a large degree the transfer of heat from discharging to incoming air. Moreover, the risk of leakage between spaces at different pressures is effectively reduced, while at the same time the securing of the parts in their respective positions is maintained simple. Other advantages of the invention will be obvious to those skilled in the art.

While there is in this application specifically described one embodiment which the invention may assume in practice, it will be understood that this embodiment of the same is shown for purposes of illustration and that the invention may be modified and embodied in various other forms without departing from its spirit or the scope of the appended claims.

What I claim as new and desire to secure by Letters Patent is:

1. In combination, in a pump, a cylinder member having a bore in which a piston is reciprocable and, in alignment and communication with said cylinder bore, an enlarged bore, fluid intake and discharge connections opening into said enlarged bore, inlet and discharge valve mechanism in said enlarged bore, inlet passage means in said valve mechanism, a head having a portion in said enlarged bore to the outside of said valve mechanism, inlet passage means in said head connecting said fluid intake connection with said inlet passage means in said valve mechanism and discharge passage means in said valve mechanism connecting directly, independently of said head, with the discharge connection opening into said enlarged bore.

2. In combination, in a pump, a cylinder member having a bore in which a piston is reciprocable and, in alignment with said cylinder bore, an enlarged bore, an intake connection opening into the side of said enlarged bore, a discharge connection opening into the bottom of said enlarged bore, a valve mechanism including inlet and discharge valves in said enlarged bore, means for connecting the inlet valve with said intake connection, and means formed in said valve mechanism for connecting the discharge valve with said discharge connection.

3. In combination, in a pump, a cylinder member having a bore in which a piston is reciprocable and, in alignment with said cylinder bore, an enlarged bore, an intake connection opening into the side of said enlarged bore, a discharge connection opening into the bottom of said enlarged bore, a valve mechanism including inlet

- and discharge valves in said enlarged bore, means for connecting the inlet valve with said intake connection, and passage means formed in said valve mechanism for connecting the discharge valve with said discharge connection, said first mentioned means including a cylinder head supported within said enlarged bore independently of said valve mechanism and having inlet passages formed therein.
10. 4. In combination, in a pump, a cylinder member having a bore in which a piston is reciprocable and, in alignment with said cylinder bore, an enlarged bore, intake and discharge connections openings respectively into said enlarged bore through different walls thereof, and inlet and discharge valve devices in said enlarged bore having connections with the points of communication of said intake and discharge connections with said enlarged bore, one of said connections provided by a cylinder head portion receivable in said enlarged bore and the other independent of said head.
5. In combination, in a pump, a cylinder member having a bore in which a piston is reciprocable and, in alignment with said cylinder bore, an enlarged bore, said cylinder member providing an annular shoulder at the junction of said bores and an annular surface surrounding the mouth of said enlarged bore, a unitary, self-contained, composite inlet and discharge valve mechanism seating on said shoulder, a head having a portion seating on said annular surface, means for clamping said head to said annular surface, sealing means at said annular surface, and means extending through said head for contacting and pressing said composite valve means with undivided pressure against said shoulder.
6. In combination, in a pump, a cylinder member having a bore in which a piston is reciprocable and, in alignment with said cylinder bore, an enlarged bore, said cylinder member providing an annular shoulder at the junction of said bores and an annular surface surrounding the mouth of said enlarged bore, combined inlet and discharge valve mechanisms seating on said shoulder, a head having a portion seating on said annular surface, sealing means at said annular surface clamped between the same and said portion, means extending through said head for pressing said composite valve means towards said shoulder, sealing means between said valve means and said shoulder, flow passage means for one of said valve mechanisms opening through said shoulder, and -flow passage means for the other valve mechanism passing through said head and through said cylinder member at a point between said two sealing means.
7. In combination, in a valve mechanism, a pair of plate members clamped together, each of which provides an annular valve seat and a valve guard, annular inlet and discharge valves each seating on the seat provided by one plate and guarded by the guard on the other, and means on said plates, including flow-reversing passage means on one of said plates, for delivering the fluid which flows past both of said valves through the outer surface of one of said plates.
8. In combination, in a valve mechanism, a pair of plates, an annular guard afforded by one of said plates and an annular valve seat afforded by the other, ports passing through the latter plate and opening through said seat, a valve coacting with said seat, a concentric series of ports in said latter plate, and means contained within said guard-affording plate for conducting fluid passing said valve to said concentric series of ports.
9. In combination, in a valve mechanism, a pair of plates, an annular guard afforded by one of said plates and an annular valve seat afforded by the other, ports passing through the latter plate and opening through said seat, a valve coacting with said seat, a concentric series of ports in said latter plate forming a ring around said annular valve seat, and smooth, continuously curved fluid-directing means within said guard-affording plate for conducting fluid passing said valve to said concentric series of ports.
10. In combination, in a pump, a cylinder member providing a cylinder bore and an enlarged coaxial bore with a shoulder at the junction of said bores, valve mechanism seated on said shoulder, a head having a sealed attachment to said cylinder member at the outer end of the latter, an inlet passage in said cylinder member opening into said enlarged bore, a coacting inlet passage in said head, an inlet passage in said valve mechanism connecting with the inlet passage in said head, means for holding said valve mechanism in position to align the inlet passage in said valve with the inlet passage in said head but permitting axial movement of said valve mechanism relative to said head, means extending through said head for forcing said valve mechanism against said shoulder, and means for sealing said forcing means against leakage along the same through said head.
11. In combination, in a pump, a cylinder member providing a cylinder bore and an enlarged coaxial bore with a shoulder at the junction of said bores, valve mechanism for said cylinder including a discharge valve having a guard member and a seat-providing member, the latter mounted on said shoulder and providing an annular series of ports concentric with the cylinder bore, and means formed wholly in said members and including a passage of increasing cross-section surrounding said enlarged bore, for delivering fluid traversing said ports.
12. In combination, in a pump, a cylinder member providing a cylinder bore and an enlarged coaxial bore with a shoulder at the junction of said bores, valve mechanism for said cylinder including a discharge valve having a guard member and a seat-providing member, the latter mounted on said shoulder and providing an annular series of ports concentric with the cylinder bore, and means formed wholly in said members and including smooth, continuously curved radial passages surrounding said cylinder bore for delivering fluid traversing said ports.
13. In combination, in a pump, a cylinder member providing a cylinder bore and an enlarged coaxial bore with a shoulder at the junction of said bores, valve mechanism for said cylinder including a discharge valve having a guard member and a seat-providing member, the latter mounted on said shoulder and providing an annular series of ports concentric with the cylinder bore, and means formed wholly in said members and including a passage of increasing cross-section surrounding said enlarged bore, and radial passages surrounding said cylinder bore, for delivering fluid traversing said ports.

RALPH E. LAMBERTON.
